UNITED STATES PATENT OFFICE.

JAMES MARION CUMMINGS, OF EVANSVILLE, INDIANA, ASSIGNOR OF ONE-HALF TO
WILLIAM MICHAEL HAHN, OF EVANSVILLE, INDIANA.

FUSE ATTACHMENT FOR ELECTRIC LIGHTS.

1,008,629.

Specification of Letters Patent. Patented Nov. 14, 1911.

Application filed January 31, 1911. Serial No. 605,734.

To all whom it may concern:

Be it known that I, JAMES MARION CUMMINGS, a citizen of the United States, residing at Evansville, in the county of Vanderburgh and State of Indiana, have invented certain new and useful Improvements in Fuse Attachments for Electric Lights, of which the following is a specification.

My invention relates to portable electric lights and has for its object the provision of a fuse for each individual light that is secured to the handle of the lamp so that should the fuse burn out it can be quickly replaced with very little trouble and without making it necessary to stop the current while doing so.

My invention will be described in detail hereinafter and illustrated in the accompanying drawings in which—

20 Figure 1 is a view of a portable electric light showing my improved fuse attachment mounted thereon, Fig. 2, a longitudinal sectional view of the fuse attachment, and Fig. 3, a cross section.

25 In the drawings similar reference characters will be used to designate corresponding parts in the several views.

My improved attachment is installed on the handle 1 of a portable electric light or 30 torch 2, said handle being made preferably of non-conducting material such as rubber, fiber, or the like and formed tubular to receive the power wires A.

My invention consists in forming the handle 1 with a fuse box 3, having angular contact pieces 4 secured in its ends to which the power wires A and the wires connected to the light 2 are secured.

35 5 indicates a plate that forms a cover for the fuse block, also made of non-conducting material and having side flanges 6 and a longitudinal spine or rib 7 in its middle and forming two channels 8 in the under side of the plate.

40 9 indicates contact pieces formed of spring material, such as copper strips, bent to angular form as shown in Fig. 2, and secured in the ends of channels 8, the projecting flanges 10 of the strips serving to engage

the contact pieces 4 and hold the plate 5 from displacement.

11 indicates the fuses secured to the contact pieces 9 by means of screws or other fastening means 12.

When in operation it will be understood that should the torch or its connections touch a metal structure, such as a piece of machinery, so that the current is short-circuited, the effect would be to burn out one or both fuses 11, but as said fuses are located only in the branch circuit to the single lamp or torch, only the one lamp will be darkened, and the location of the fuse box on the handle of the torch makes the replacing of the burned out fuse a simple matter, easily and quickly accomplished.

Having thus described my invention what I claim is—

1. In combination with a portable electric light having a handle formed with a recess, contact pieces secured in said recess, the power wires and light-circuit wires secured to said contact pieces, a removable cover for said recess, spring contact pieces secured to said cover and adapted to engage the contact pieces in the recess and hold the cover from displacement, and fuses connecting said spring contact pieces on the cover.

2. In combination with a portable electric light having a handle formed with a recess, contact pieces secured in the ends of said recess, the power wires and light circuit wires secured to said contact pieces, a removable cover for said recess having downwardly extending side flanges and an intermediate spine or rib forming the inner side of the cover with two channels, spring contact pieces secured in said channels and adapted to engage the contact pieces in the recess and hold the cover from displacement, and fuses connecting said spring contact pieces on the cover.

In testimony whereof I hereto affix my signature in the presence of two witnesses.

JAMES MARION CUMMINGS.
